UNITED STATES PATENT OFFICE.

EDWARD G. ASHLEY, OF ROCHESTER, NEW YORK.

DESIGN FOR A BICYCLE-SADDLE SPRING.

SPECIFICATION forming part of Design No. 33,519, dated November 6, 1900.

Application filed October 11, 1900. Serial No. 32,794. Term of patent 7 years.

To all whom it may concern:

Be it known that I, EDWARD G. ASHLEY, a citizen of the United States, and a resident of Rochester, in the county of Monroe and State of New York, have invented and produced a certain new and original Design for Bicycle-Saddle Springs, of which the following is a specification.

Figure 1 is a perspective view of a bicycle-saddle spring, showing my new design. Fig. 2 is a plan view, and Fig. 3 an end view, of the same.

As shown in the drawings, the leading feature of my design consists of a wire spring made from a single piece and consisting of two corresponding rearwardly-extending portions, both bent outwardly and then respectively extended forwardly and at the same time curved inwardly, then both extended backwardly in the same plane with the first-mentioned portions, and finally bent downwardly and continued forwardly in an upward curve in two parallel portions which lie, re-

spectively, beneath the last-named portions and which are united in a loop.

A A represent the rearwardly-extending portions, which are curved outwardly, respectively, in the curves B B. From the curves B B said portions of the spring are curved, respectively, forwardly and inwardly in the curved portions C C and are united by the curves D D, respectively, with the straight and approximately parallel portions E E. The portions E E terminate in the downward curves F F, and these in turn terminate in the forwardly-extending and upwardly-curved portions G G, which latter are approximately parallel. The last-named portions are united in the curve H.

What I claim is—

The design for a bicycle-saddle spring substantially as shown and described.

EDWARD G. ASHLEY.
